[57] **CLAIM**

The ornamental design for a compact enclosed motor control, as shown and described.

DESCRIPTION

FIG. 1 is a perspective view of a compact enclosed motor control showing our new design;

FIG. 2 is a perspective view of a compact enclosed motor control showing a second embodiment of our new design;

FIG. 3 is a perspective view of a compact enclosed motor control showing a third embodiment of our new design;

FIG. 4 is a right elevational view of the first embodiment, the left elevational view being a mirror image;

FIG. 5 is a bottom plan view of the first embodiment;

FIG. 6 is a top plan view of the first embodiment;

FIG. 7 is a right elevational view of the second embodiment, the left elevational view being a mirror image;

FIG. 8 is a top plan view of the second embodiment;

FIG. 9 is a bottom plan view of the second embodiment;

FIG. 10 is a right elevational view of the third embodiment;

FIG. 11 is a top plan view of the third embodiment;

FIG. 12 is a bottom plan view of the third embodiment.

The rear surface of each embodiment is flat and unornamented and is also hidden in normal use.

*Fig. 1.**Fig. 6.**Fig.2.**Fig.3.**Fig. 4.**Fig. 5.**Fig. 7.**Fig. 8.**Fig. 9.**Fig. 10.**Fig. 11.**Fig. 12.*
